[57] ABSTRACT

In a fuel injection pump associated with an internal combustion engine, the fuel quantities injected during each pressure stroke on the one hand and the injection start on the other hand are separately regulated as a function of the engine-rpm by two groups of centrifugal weights, each group displacing a separate governor member moving independently from the other.

RPM REGULATOR FOR A FUEL INJECTION PUMP SERVING AN INTERNAL COMBUSTION ENGINE

BACKGROUND OF THE INVENTION

This invention relates to an rpm regulator for a fuel injection pump associated with an internal combustion engine and is of the type that includes a centrifugal governor having a first group of centrifugal weights actuating the fuel quantity control member of the fuel injection pump and a second group of centrifugal weights affecting the position of a timing member that determines the injection start during each pressure stroke of the fuel injection pump.

In a known rpm regulator of the aforesaid type, as disclosed, for example, in U.S. Pat. No. 2,274,609, it is not possible to actuate the fuel quantity control member separately from the timing member for the entire rpm range.

OBJECT AND SUMMARY OF THE INVENTION

It is an object of the invention to provide an improved rpm regulator of the aforesaid type which permits the aforesaid separation between the control of fuel quantity and timing and which, furthermore, has a simple and economical structure.

Briefly stated, according to the invention, each group of centrifugal weights is effective through a separate governor sleeve.

The invention will be better understood as well as further objects and advantages become more apparent from the ensuing detailed specification of a preferred, although exemplary embodiment taken in conjunction with the drawing.

BRIEF DESCRIPTION OF THE DRAWING

FIG. 1 is a schematic, partially sectional view of the preferred embodiment with parts of the fuel injection pump;

FIG. 2 is a view in the direction of the axis of rotation, of the arrangement of the centrifugal weights and

FIG. 3 is an axial view of a part of the regulator and the fuel injection pump.

DESCRIPTION OF THE EMBODIMENT

In an only symbolically illustrated housing 1 of a fuel injection pump for a four-cylinder internal combustion engine there journals a pump drive shaft 2. The latter is coupled with a radial cam disc 3 which carries four cams 4 (that is, as many cams as there are cylinders in the engine). The cam track of the cam disc 3 engages rollers 5 which, in turn, journal about pins 6 stationarily supported in the housing 1. There is further provided a pump-and-distributor member 8 which, at its driven end, has a collar 9 which, in turn, is coupled by means of a pin 10 with the cam disc 3.

Under the effect of a spring 11 the cam disc 3 is pressed into continuous contact with the rollers 5. The pump-and-distributor member 8 slides in a pump body 12 which is closed by means of a plug 13.

The inner chamber 14 of the fuel injection pump is filled with slightly pressurized fuel taken from a source, not shown. From the chamber 14 there extends an inlet channel 15 which cooperates with four longitudinal, axially parallel extending grooves 16 provided in the lateral face of the pump-and-distributor member 8. The longitudinal grooves 16 are in communication with a

5 pump work chamber 17 and with an annular groove 18 provided on the pump-and-distributor member 8. From the annular groove 18 there extends a distributor groove 19 in the pump-and-distributor member 8 for cooperation with four outlet channels 20 (only one shown).

10 The inlet channel 15 is offset with respect to the outlet channels 20 in such a manner that, dependent upon the position of the pump-and-distributor member 8, either the inlet channel 15 communicates with one of the axial grooves 16 or the distributor groove 19 communicates with one of the outlet channels 20. Each of these outlet channels 20 leads to a spring-biased pressure valve 22 to which there is coupled an injection conduit 15 (not shown) leading to a fuel injection nozzle (also not shown) associated with an engine cylinder.

From the pump work chamber 17 there extends, within the pump-and-distributor member 8, an axial channel 23 to a radial port 24 and to four radial channels 25 (FIG. 3). A control sleeve 26 is mounted for axial and angular displacement on the pump-and-distributor member 8. The radial face 27 of the control sleeve 26 cooperates with the radial port 24. Into the other, opposite radial face of the control sleeve 26 there is machined an oblique control surface 28 which cooperates with the radial channels 25.

To the drive shaft 2 there is keyed a spur gear 29 which meshes with a spur gear 30. The latter is affixed to the hub of a cage 31 which is fixedly attached to a setting shaft 32 journaling in the housing 1. In the cage 31 there are swingably arranged two groups of centrifugal weights 33 and 34, respectively. As shown in FIG. 2, the first group comprises four centrifugal weights 33 which are in engagement with a governor sleeve 35. The second group is formed of two centrifugal weights 34 which, in turn, engage a governor sleeve 36. The governor sleeves 35 and 36 are telescopically disposed; the governor sleeve 35 is guided on the setting shaft 32.

35 The first group of centrifugal weights serves for the rpm-dependent alteration of the delivered fuel quantities of the fuel injection pump and for this purpose actuates, through the governor sleeve 35, a lever 37 which, after swinging freely along a short path, engages a lever 38. The levers 37 and 38 are connected to resetting springs 41 and 42, the bias of which is variable by means of a lever 43. The latter is carried at one end of a pin 44 supported in the housing 1. The other end of the pin 44 carries an arbitrarily adjustable setting lever 45 which, in its shown terminal position, engages an abutment pin 46.

40 The second group of centrifugal weights serves for shifting the starting moment of the injection and for this purpose actuates through the governor sleeve 36 a lever 48 which is connected to a resetting spring 49 attached to a post 50 fixedly secured to the housing 1.

45 The levers 37 and 38 are pivotally held by a pin 51. The lever 37 has two arms; its arm 37' carries a sphere 52 which projects into a longitudinal depression 53 provided in the control sleeve 26. The lever 48 which 50 also has two arms, is pivotable about a support pin 54 and extends with its spherical end 48' into a circumferentially oriented depression 55 provided in the control sleeve 26.

55 When the engine is running, the drive shaft 2 of the pump, the cam disc 3 and the pump-and-distributor member 8 coupled to the drive shaft 2 rotate with an rpm that is a function of the engine rpm. The cam disc

3, in cooperation with the rollers 5 causes an axial reciprocating motion of the pump-and-distributor member 8 in addition to its rotation. The cam disc 3 is maintained in continuous contact with the rollers 5 by virtue of the spring 11. The pump-and-distributor member 8 is shown in FIG. 1 in its lower dead center. The pump work chamber 17 is charged with fuel through the inlet channel 15. As the cam disc 3 rotates, first the inlet channel 15 is closed by the lateral face of the pump-and-distributor member 8, a precondition for starting, the effective pressure stroke of the pump-and-distributor member 8. During the course of the effective pressure stroke fuel is delivered from the pump work chamber 17 through the channels 16 into the annular groove 18 and therefrom through the distributor groove 19 into one of the outlet channels 20 and through the associated pressure valve 22 to a fuel injection nozzle of the internal combustion engine.

The beginning and the end of the injection is determined by virtue of the cooperation of the frontal face 27 of the control sleeve 26 with the channel 24 and the control face 28 with one of the channels 25. The effective pressure stroke begins when the channel 24 is closed by the control sleeve 26 and terminates when the control face 28 opens the channel 25.

The duration of injection and thus the injected fuel quantities may be altered by rotating the control sleeve 26 with the aid of the lever 37, 37', whereas the beginning of injection may be shifted by means of an axial displacement of the control sleeve 26 with the aid of the lever 48.

The aforescribed rpm regulator operates as follows:

As the pump drive shaft 2 rotates, the setting shaft 32 of the control apparatus is also rotated by the spur gears 29 and 30. Thus, in case of an rpm increase the centrifugal weights 33 and 34 move outwardly and displace the governor sleeves 35 and 36 to the right as viewed in FIG. 1.

The governor sleeve 35, during its aforesaid rightward displacement, first causes the lever 37, 37' to pivot against the force of the relatively weak and soft spring 41 until the lever 37, 37' engages the lever 38. Since the lever 45 is in engagement with the abutment 46 and the spring 42 has only a weak bias, the centrifugal weights 33, after the internal combustion engine is started, also cause a pivotal motion of the lever 38, so that the control sleeve 26 sets the oblique control face 28 for a smaller fuel quantity. Thus, the fuel quantity will be decreased from the starting fuel quantities to the quantities necessary for the idling run of the engine.

It is thus seen that with the adjusting lever 45 there may be set an arbitrary engine rpm which is maintained with the rpm regulator. By means of the pivotal motion of this lever, the state of tensioning and thus the resetting force of the springs 41 and 42 is altered. Consequently, there is determined an rpm at which the centrifugal weights 33, after engagement of the lever 37, 37' with the lever 38, overcome the force of the spring 42 and lift the lever 38 from an abutment 56 which determines the full load fuel quantities. In this manner the control sleeve 26 is again rotated, so that the oblique control face 28 of the control sleeve 26 sets a fuel quantity which is necessary for maintaining the desired rpm.

The two centrifugal weights 34 affecting the governor sleeve 36 pivot against the force of the spring 49 as

the rpm increases and cause, through the governor sleeve 36, a pivotal motion of the lever 48 which thus axially displaces the control sleeve 26. As a result, the position of the radial face 27 with respect to the channel 24 changes and, as a result, the moment of injection start of the fuel injection pump is varied.

Since the two groups of centrifugal weights actuate separate governor sleeves 35 and 36, a quantity setting of the fuel injection pump is possible throughout the entire rpm range independently from the setting of the injection start. In addition, the described rpm regulator is of simple, economical structure.

What is claimed is:

1. In an rpm regulator for a fuel injection pump serving an internal combustion engine, said fuel injection pump being of the known type that has (a) a rotary component having an engine-rpm dependent rotational speed, (b) a fuel quantity control member, the position of which determines the fuel quantities delivered to said engine for injection, (c) a timing member, the position of which determines the movement of injection start during each pressure stroke of the pump, said rpm regulator being of the known type that has (a) a first group of centrifugal weights secured to said rotary component and affecting the position of said fuel quantity control member, (b) a second group of centrifugal weights secured to said rotary component and affecting the position of said timing member, (c) resetting spring means opposing the force of said centrifugal weights exerted on said members, the improvement comprising
  - A. a first sleeve-like governor member connected to said centrifugal weights forming said first group to be displaced by the latter to an rpm-dependent extent,
  - B. a first coupling means connecting said first governor member to said fuel quantity control member,
  - C. a second sleeve-like governor member connected to said centrifugal weights forming said second group to be displaced by the latter to an rpm-dependent extent, said first and said second sleeve-like governor members being telescopic and displaceable independently from one another and
  - D. a second coupling means connecting said second governor member to said timing member.
2. An improvement as defined in claim 1, including a setting shaft supporting at least indirectly said centrifugal weights, said setting shaft having an axis about which said centrifugal weights rotate, said inner governor sleeve being slidably disposed on said setting shaft.
3. An improvement as defined in claim 1, wherein said first and second coupling means are constituted by separate levers, said resetting spring means engaging said separate levers.
4. An improvement as defined in claim 1, wherein said fuel injection pump includes
  - A. a pump body,
  - B. a pump work chamber provided in said pump body,
  - C. a pump-and-distributor member disposed at least partially in said pump body and connected to said rotary component to be rotated by the latter, said pump-and-distributor member cooperating with said pump work chamber,
  - D. means connected to said rotary component and said pump-and-distributor member for causing axial reciprocation of the latter,

- E. a channel means extending within said pump-and-distributor member, said channel means communicating with said pump work chamber and having a terminal opening on the lateral face of said pump-and-distributor member and
- F. a control sleeve movably mounted on said pump-and-distributor member and opening and closing said channel means during rotation and reciprocation of said pump-and-distributor member at deter-

5
mined moments dependent upon the position of said control sleeve, said control sleeve constituting both said fuel quantity control member and said timing member, said control sleeve being connected to said first group of centrifugal weights through said first coupling means and to said second group of centrifugal weights through said second coupling means.
